(57) **CLAIM**

The ornamental design for a data communication antenna as shown and described.

DESCRIPTION

1. Data communication antenna

1.1: Front Perspective

1.2: Right

1.3: Left

1.4: Back

1.5: Front

1.6: Top

1.7: Bottom.

The design relates to a data communication antenna; and the characteristic features lie in the shape as shown.

The broken lines in the drawings depict portions of the data communication antenna that form no part of the claimed design.
